UNITED STATES PATENT OFFICE.

FRANK M. SANDERSON, OF SWAMPSMOTT, MASSACHUSETTS, ASSIGNOR TO GENERAL ELECTRIC COMPANY, A CORPORATION OF NEW YORK.

TAPPING MACHINE.

Application filed November 30, 1921. Serial No. 518,939.

To all whom it may concern:

Be it known that I, FRANK M. SANDERSON, a citizen of the United States, residing at Swampscott, in the county of Essex, State 5 of Massachusetts, have invented certain new and useful Improvements in Tapping Machines, of which the following is a specification.

This invention relates to tapping machines and has for its object the provision of improved means whereby the tapping element is given its axial as well as its rotary movement in a simple, reliable and efficient manner.

15 More particularly my invention relates to automatic machines for tapping nuts, although it obviously has various other applications. In automatic tapping machines it is desirable to move the tap axially into engagement with the work by a yieldable force thereby avoiding an overload on the tap due to forcing it through the work faster than the pitch of the threads will allow and also damage when an undrilled 20 blank is fed to the tap, and a further object of my invention is to provide an improved construction which will meet these conditions in a satisfactory manner.

In carrying out my invention I employ 30 helical gears, the end thrust of which provide the axial movement of the tap with relation to the work. When the tap is rotated in the tapping direction it will be moved by the end thrust of the helical gears 35 into engagement with the work and upon reversal of the direction of rotation it will be moved out of engagement with the work by the end thrust of the helical gears.

In case the tap as it rotates is moved into 40 engagement with a blank or undrilled piece of work it will be held against the blank or work by a force equal to the end thrust of the gears. Since the end thrust has a definite maximum value, the tap is in effect 45 yieldably held against the blank or undrilled piece of work, whereby damage to the tap is avoided.

For a consideration of what I believe to 50 be novel and my invention, attention is directed to the accompanying description and the claims appended thereto.

Figure 1 is a side elevation of my invention, partly in section showing the arrangement of the different elements; Figure 2 is 55 a plan view of Fig. 1 with the cover re-

moved; Figure 3 is a view partly in section, along line 3-3 of Fig. 2 looking in the direction of the arrows; Figure 4 is an end view of the driven shaft showing the friction retarding means and method of 60 securing the same; and Figure 5 is a perspective view showing some of the elements of my invention and their relation to each other.

Referring to the drawing, 10 indicates a 65 base or framework on which is journaled a shaft 11 which carries a worm 12 and a pulley 13. Shaft 11 may be driven by any suitable means. In the present instance it is shown as being driven by the pulley 13 which is belted to any suitable source of power. Meshing with the worm 12 is a worm gear 14 which is supported by the base 10 and has a projecting stud 15 upon which one end of a link 16 is journaled. 70 The other end of link 16 is journaled to a movable stud 17 mounted in slot 18 of a segmental gear 19. The radial slot 18 makes it possible to adjust the travel of segmental gear 19. The segmental gear 19 is mounted 75 on a stub shaft 20 supported by base 10 and meshes with a pinion 21 mounted on a shaft 22 which carries a helical gear 23. Stub shaft 20 is supported by the base 10. The helical gear 23 meshes with a helical pinion 80 24 which is of greater length than the thickness of gear 23 and is cut or mounted on a shaft 25 journaled to the frame 10. Shaft 25 carries a chuck 26 and a tap 27 on one end and a friction retarding means on the 85 other. The friction retarding means comprises a forked member 28 which is loosely mounted on shaft 25 and has a plurality of discs 29 composed of leather or like material disposed on each side of it and held 90 in place by discs 30 which are keyed to a shaft 25. The discs 30 are free to move axially on the shaft 25. A nut 31 is screw threaded on the end of shaft 25 for the purpose of varying the friction means. A rod 95 32 fastened to the base or frame work 10 prevents the forked member 28 from turning with shaft 25.

Associated with the above described elements is a hopper 33 which feeds the articles to be threaded to the tap. The hopper 105 33 is mounted upon rods 34 and secured thereto by any suitable means. As shown this means consists of a frame work composed of tubular members 34 and end 110

pieces 34^b and 34^c. This framework can be set at any desirable point along the rods 34, the hopper 33 being fastened in an upright position on member 34^b. A spring member 36 having a slot 45 is located below the hopper 33 and supported on a stud 37 projecting from the casing. The spring member 36 is secured to the stud 37 by means of a member 38 and a set screw 39. The upper end 10 of spring member 36 is biased against a pin 40 on a sliding rod 41 by a spring 42. A roller 43 is mounted on the inner end of sliding rod 41 and rolls on a side of segmental gear 19 and a cam or raised surface 15 44 which is provided for actuating the hopper discharge device as it rolls under roller 43.

The operation is as follows: As shown in the drawing a nut is being tapped. The tap 20 is proceeding through the nut in a right hand direction (Figs. 3 and 5). Assume that the segmental gear 19 (Fig. 1) has begun to travel in a counterclockwise direction and that the tap 27 is about to engage 25 the nut to be tapped. As the segmental gear 19 continues in counterclockwise direction the helical gear 23 (Fig. 1) will rotate in a clockwise direction and cause the tap to rotate in a counterclockwise or right- 30 hand tapping direction and at the same time cause the tap to be thrust toward the nut by reason of the thrust caused by the helical gears. As the segmental gear 19 continues in the above direction the raised or cam 35 surface 44 (Fig. 1) on segmental gear 19 will approach the roller 43 (Fig. 3) on the sliding rod 41 which operates the hopper discharge mechanism. When the roller 43 comes in contact with the surface 44 the 40 slot 45 (Fig. 3) will be moved adjacent the last nut tapped and will allow it to drop from the machine. It will be noticed that the nut being tapped as well as those in the hopper are supported by the tap when the 45 discharge of the finished nut takes place.

Assume now that the segmental gear 19 has reversed its direction of travel. This will reverse the direction of rotation of the tap and also the direction of the aforementioned thrust due to the helical gears.

This will cause the tap to be drawn from the nut. At the same time the cam surface 44 will pass from under the roller 43 and allow the discharge mechanism to close the 55 hopper in time to catch the finished nut as it drops off the tap. This nut will provide a support for the next nut to be tapped.

The friction device on the end of shaft 25 operates as follows: The discs 30 being 60 fixed on the shaft 25 will rotate and cause the friction discs 29 to also rotate. As the discs 29 rub against stationary forked member 28 a load will be created on shaft 25. This will insure the lateral movement of the 65 shaft 25 in response to the end thrust of

the helical gears when the tap is not in contact with a nut.

One of the advantages of my invention over the machines now in general use for tapping small articles is that I have dispensed with the use of reversing clutches in the driving elements and have thereby reduced the vibration and wear due to the shifting of same.

Another advantage is that the direction 75 of rotation of driving means is immaterial as my machine will work equally well when driven in either direction and further after having once started in a given direction there is no need of any reversal in the driving means. I therefore am able to also dispense with the need of shifting belts, in the event of a line shaft drive and electrical connections in the event of a direct motor drive. And further in the event of a blank 80 nut or undrilled work piece being fed to the tap no damage will be done as might be the case if the tap were driven axially by other means. The end thrust of the gears having a certain definite value will cause 85 the tap to be pressed against the blank work piece by a force equal to the end thrust and at the same time permit the tap to rotate. As soon as the tap has completed a tapping cycle the blank work piece will be 90 discharged from the machine in the usual manner without any need of stopping the machine to remove it.

In accordance with the provisions of the 95 patent statutes, I have described the principle of operation of my invention, together with the apparatus which I now consider to represent the best embodiment thereof, but I desire to have it understood that the apparatus shown is only illustrative and 100 that the invention can be carried out by other means.

What I claim as new and desire to secure 105 by Letters Patent of the United States, 110 is:

1. In a tapping machine, a thread cutting tool, a shaft having axial and rotary movement supporting said tool, a helical driving gear for the shaft, means for imparting oscillatory movement to said driving gear, and a helical pinion on the shaft with which the gear meshes, said pinion being of greater length than the thickness of the gear.

2. In a tapping machine, a thread cutting tool, a shaft having axial and rotary movement supporting said tool, a helical driving gear for the shaft, means for imparting oscillatory movement to said driving gear, a helical pinion on the shaft with which the gear meshes, said pinion being of greater length than the thickness of the gear, and means connected with the shaft 125 for imparting thereto an adjustable brak- 130

3. In a tapping machine, a thread cutting tool, a shaft having axial and rotary movement supporting said tool, a helical segmental driving gear for the shaft, means for imparting oscillatory movement to said driving gear, a helical pinion carried by the shaft with which the gear meshes, said pinion being of greater length than the thickness of the gear whereby the pinion is permitted to move axially in response to the end thrust thereon while in mesh with the driving gear, means connected with the shaft for imparting thereto a braking load, a hopper, a movable member below the hopper having a slot which registers with the hopper when the member is moved, a cam surface on the driving gear, and follower means for the cam connected with the member for moving the latter to carry the slot into registration with the hopper.
4. In a tapping machine, a thread cutting tool, a rotating shaft having axial movements supporting said thread cutting tool, helical gears driving said shaft, and a friction means on said shaft, the end thrust of the helical gears being utilized to impart axial movement to said shaft.
5. In a tapping machine, a driving shaft having a uniform direction of rotation, a tool supporting shaft, and means comprising a link and helical gears for imparting a forward and reverse direction of rotation and a forward and reverse axial thrust to the tool supporting shaft.
6. In a machine for tapping nuts, a tool supporting shaft having forward and reverse rotary and axial movements, a helical gear driving said tool supporting shaft, means connected with said gear for imparting thereto an oscillatory movement, a helical pinion carried by the shaft, said pinion being in meshing engagement with the gear and being of greater length than the thickness of the gear, the length of the pinion being such that said meshing engagement is maintained throughout the length of the axial movements of the shaft, the end thrust of said helical gear being utilized to impart the axial movements to said shaft through the intermediary of the pinion, a work holding member, a hopper, and means associated with said hopper for automatically supplying work pieces to said work holding member.
7. In a tapping machine, a thread cutting tool, a shaft supporting said thread cutting tool, and helical gears driving said shaft, one of said gears being in the form of an elongated pinion carried by the shaft, said helical gears being arranged to give an inward thrust on the shaft during the tapping operation and an outward thrust on the shaft during the removal operation of the tool, and said shaft being axially movable in response to said inward and outward thrusts.

In witness whereof, I have hereunto set my hand this 28th day of November, 1921.

FRANK M. SANDERSON.
